UNITED STATES PATENT OFFICE.

JAMES T. GERMANY, OF NEW ORLEANS, LOUISIANA, ASSIGNOR OF ONE-HALF TO
ISAAC BLOCH, OF NEW ORLEANS, LOUISIANA.

CHANCE DEVICE.

1,116,264.

Specification of Letters Patent.

Patented Nov. 3, 1914.

Application filed April 23, 1912. Serial No. 692,569.

To all whom it may concern:

Be it known that I, JAMES T. GERMANY, a citizen of the United States, residing at New Orleans, in the parish of Orleans and 5 State of Louisiana, have invented new and useful Improvements in Chance Devices, of which the following is a specification.

This invention relates to chance devices and the principal object of the invention is 10 the provision of a simple and efficient means for determining winners.

The device essentially consists of a board provided with a plurality of sockets and apertures which are covered with a sheet of 15 suitable frangible material having a concealed circuit communicating with certain of the apertures from their opposite ends, the object being to close the circuit thus sounding a signal by blindly inserting a suitable 20 tool into the sockets and apertures, it of course being understood that the circuit is closed only when the plug is inserted in one of the apertures.

Further objects of this invention will appear as the following specific description is 25 read in connection with the accompanying drawing, which forms a part of this application, and in which:—

Figure 1 is a front elevation. Fig. 2 is a 30 vertical section taken therethrough. Fig. 3 is a plan view of the device with the front board removed. Fig. 4 is an elevation of the tool employed.

Referring more particularly to the drawing, the device consists essentially in a back board 1 and a front board 2, the latter being provided with a plurality of apertures 3 and 4, the latter extending entirely through the board and the apertures 3 being in the 35 form of sockets which extend approximately half way through the board. The back board carries a suitable type of buzzer 5 which is connected in circuit with a battery 6 carried in the casing 7 secured to the back 40 board. The battery and buzzer are also connected to a pair of parallel conductors 8 which are arranged, as shown in Fig. 3, upon the back board and exposed through the apertures 4, as shown in dotted lines at 45 50 9 on Fig. 3. This arrangement may be va-

ried to extend the conductors across any apertures of the board. By reason of this fact the conductors 8 may be shifted to provide a new combination of electrified apertures every time it is necessary to cover the face 55 of the board with a new sheet of frangible material, thus adding to the interest of the game.

Covering the front board is a sheet of some material which may be punctured by a 60 suitable metallic tool, the sheet here shown being shown in the form of a paper sheet 10 having printed rings 11 thereon to correspond with the apertures 3 and 4 in the board. This paper effectually conceals the 65 wires or conductors at the bottom of the apertures 4.

In playing the game, the operator takes a tool, such as is shown in Fig. 4, which consists of an insulating handle 12 and a metallic punch 13 and forces it through the paper into one of the apertures. If the pin engages one of the apertures 3, nothing happens but if it enters one of the apertures 4, the conductors 8 will be bridged and the 75 circuit completed through the battery to the buzzer.

What is claimed is:—

A device of the class described comprising a board having a plurality of sockets 80 and a plurality of through apertures therein, a pair of separate conductors extending across certain of the apertures, a source of current and a signal device connected in the circuit with said conductors, a frangible 85 sheet covering the sockets and apertures and concealing the conductors, an electrically separate metallic tool for punching out the frangible sheet and bridging the conductors, a back plate covering and retaining the conductors in any desired position, and supporting the signal device, and indicia printed on the sheet to show the position of the 90 sockets and apertures.

In testimony whereof I affix my signature 95 in presence of two witnesses.

JAMES T. GERMANY.
